(57) **CLAIM**

The ornamental design for a drip accessory for humidifier, as shown and described.

DESCRIPTION

FIG. 1 is a front elevation view of a drip accessory for humidifier showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is another perspective view thereof; and,

FIG. 9 is a perspective view of the drip accessory for humidifier as it would be positioned during use.

The broken lines of FIG. 9 depicting a humidifier represent environmental structure that forms no part of the claimed design. The remainder of the broken lines depict portions of the article that form no part of the claimed design.
